ABSTRACT

A circuit for generating voltages having values proportional to the threshold voltages (V_T) of n-channel transistors used in the circuit comprises a current mirror M_2, M_3 having a reference current input generated from a reference voltage of value $2V_T$ by an n-channel transistor M_1 . The output reference voltage of value $2V_T$ by an n-channel transistor M_4 whose gate is coupled either to its drain, for output voltages greater than V_T , or to the gate of transistor M_1 for output voltages less than V_T .

THRESHOLD DEPENDENT VOLTAGE SOURCE

BACKGROUND OF THE INVENTION

This invention relates to voltage sources and particularly to circuits which provide specific voltages which are dependent on the threshold voltage of transistors used in the circuit.

Such circuits are particularly useful in the field of CMOS IC's where it is advantageous to provide specific voltages whose values are proportional to the threshold voltage V_T of the transistors used therein. Such transistors may be either n- or p-channel field-effect transistors. One application is in logic circuits where threshold voltage dependent voltages are required in order to switch the transistors in the circuit so that logical decisions are made by the circuit. Another application is in sensing amplifiers in which lines connected to the inputs of the amplifier are precharged by voltages proportional to the threshold voltage in order to improve the sensitivity of the amplifier.

SUMMARY OF THE INVENTION

Therefore it is an object of the invention to provide a circuit which generates voltages whose values are proportional to the threshold voltage of the transistors used in the circuit.

Accordingly, the invention provides a voltage source circuit comprising a current mirror having an input and an output and coupled to a first reference potential line;

a reference current source coupled to the current mirror input or generating a reference current which is proportional to a threshold voltage; and

a bias transistor having a first current electrode coupled to the current mirror output, a second current electrode coupled to a second reference potential line and a control electrode coupled so as to produce at its first current electrode a voltage dependent on the reference current,

wherein said current mirror output forms an output of the voltage source circuit.

Preferably the reference current source comprises a transistor having a first current electrode coupled to said current mirror input, a second current electrode coupled to said second reference potential line and a control electrode for receiving an input reference voltage.

As will be more fully described below, the control electrode of the bias transistor may be coupled to receive either the input reference voltage or the voltage level at the current mirror output, depending on the required output from the voltage source circuit.

BRIEF DESCRIPTION OF THE DRAWINGS

The invention will now be more fully described by way of example with reference to the drawings of which:

FIGS. 1A and 1B show circuit diagrams of a basic embodiment of a voltage source circuit according to the invention; and

FIGS. 2A and 2B show circuit diagrams of an improved embodiment of a voltage source circuit according to the invention.

DETAILED DESCRIPTION OF THE INVENTION

Thus, FIGS. 1A and 1B show circuit diagrams of a voltage source circuit providing voltages which are

dependent on the threshold voltage of n-channel transistors. It comprises a current mirror composed of p-channel transistors M_2 and M_3 each having one current electrode coupled to a voltage supply line V_{DD} . Transistor M_2 is diode-coupled with its second current electrode coupled to its gate electrode which is also coupled to the gate electrode of transistor M_3 . The input to the current mirror comprises the second current electrode of transistor M_2 which is coupled to the first current electrode of an n-channel transistor M_1 . This transistor has its second current electrode coupled to a ground reference potential line and its gate electrode coupled to receive an input reference voltage V_{REF} .

In this embodiment of the voltage source circuit, the input reference voltage V_{REF} is arranged to be twice the threshold V_T of the n-channel transistors. Thus:

$$V_{REF} = 2 V_T \quad (0)$$

Since the current I through a transistor having a threshold voltage V_T and biased by a voltage V is described by

$$I = K (V - V_T)^2$$

where K is the transistor gain constant, the current through transistor M_1 is

$$I_1 = K_1 (2 V_T - V_T)^2 = K_1 V_T^2 \quad (1)$$

This is the current input to the current mirror and the current output from the mirror through transistor M_3 is:

$$I_3 = x I_1 = x K_1 V_T^2 \quad (2)$$

where x is a constant determined by the geometry ratios of transistors M_2 and M_3 .

The output of the current mirror is coupled to the drain of an n-channel bias transistor M_4 , this drain forming the output of the voltage source circuit. The source of transistor M_4 is coupled to the ground reference potential line and the gate of transistor M_4 is connected either to its own drain (FIG. 1A) or the gate electrode of transistor M_1 (FIG. 1B) depending on the output voltage required from the voltage source circuit.

If the gate electrode of transistor M_4 is coupled to its drain, as shown in FIG. 1A its drain source voltage V_4 is determined by:

$$I_3 = K_4 (V_4 - V_T)^2 \quad (3)$$

Rearranging this, gives:

$$V_4 = V_T + \sqrt{I_3 / K_4} \quad (4)$$

Substituting for I_3 from equation (2) gives:

$$\begin{aligned} V_4 &= V_T + \sqrt{x K_1 V_T^2 / K_4} \\ &= V_T (1 + \sqrt{x K_1 / K_4}) \end{aligned} \quad (5)$$

Thus the output voltage V_4 can be made to be any predetermined ratio of V_T greater than one by appropriately choosing $x K_1 / K_4$.

Similarly, if the gate electrode of transistor M_4 is coupled to the gate electrode of transistor M_1 as shown

in FIG. 1B, the transistor M_4 can be made to operate in the triode region. In this case, the output voltage V_4 is given by:

$$(6) \quad I_3 = K_4[2(2V_T - V_T)V_4 - V_4^2] \\ = K_4(2V_T V_4 - V_4^2)$$

Substituting for I_3 from equation (2) gives:

$$(7) \quad V_4^2 - 2V_T V_4 + xK_1 V_T^2 / K_4 = 0$$

whose solution is:

$$(8) \quad V_4 = V_T(1 - \sqrt{1 - xK_1/K_4})$$

From this it can be seen that the output voltage V_4 can now be made to be lower than the threshold voltage V_T by appropriate choices of x , K_1 and K_4 .

Thus, by coupling the gate of transistor M_4 to the gate of the transistor M_1 , the ratio V_4/V_T is less than one and by coupling the gate of transistor M_4 to the drain of transistor M_4 , the ratio V_4/V_T is greater than one.

Although the above calculations were performed for $V_{REF}=2V_T$, it will be appreciated that a similar result will be obtained for V_{REF} being any value $(n+1)V_T$. In this case:

$$(9) \quad I_1 = K_1((n+1)V_T - V_T)^2 = K_1(nV_T)^2$$

so that for the gate of the transistor M_4 being coupled to its drain we have, similarly to equations (2) and (3):

$$(10) \quad I_3 = xI_1 = xK_1(nV_T)^2 \\ = K_4(V_4 - V_T)^2$$

Thus:

$$(V_4 - V_T)^2$$

giving:

$$\sqrt{xK_1/K_4} nV_T = V_4 - V_T$$

so that

$$(11) \quad V_4 = V_T[1 + n\sqrt{xK_1/K_4}]$$

To generate a current in transistor M_1 , n must be greater than zero. However when V_{REF} is generated by diode-connected transistors connected in series, to realise ratios V_{REF}/V_T larger than two i.e. three or four or more, requires higher values of the supply voltage V_{DD} . Therefore a useful compromise is to set $V_{REF}=2V_T$.

One circuit in which a voltage V_{REF} with a value of approximately $2V_T$ is generated is shown in FIGS. 2A and 2B. In these Figures transistors M_1 - M_4 are equivalent to those in FIGS. 1A and 1B, respectively and the output voltage is V_4 . The reference voltage $V_{REF}=V_1$ is generated by resistor R and by transistors M_{01} , M_{02} , connected in series between voltage supply line V_{DD} and reference potential line. However, the reference voltage V_{REF} will not be exactly $2V_T$ because of trans-

sistors M_{01} and M_{02} which are diode-coupled, across which the voltage will be:

$$(11) \quad V_1 = 2V_T + 2\sqrt{I_0/K_0}$$

where I_0 is the current through the transistors M_{01} and M_{02} and K_0 is their gain constant.

However neither I_0 nor K_0 can be considered as having constant values since I_0 depends on the supply voltage V_{DD} and K_0 is a function of process parameters and temperature. In the circuit of FIG. 1 and referring to equation (0) the current I_3 controlled by voltage V_1 would be:

15

35

40

45

50

55

60

65

$$(12) \quad I_3 = xK_1(V_T + 2\sqrt{I_0/K_0})^2$$

$$= xK_1(V_T^2 + 4V_T\sqrt{I_0/K_0} + 4I_0/K_0)$$

This current will be fed to transistor M_4 .

To obtain a precise ratio of V_4/V_T equal to $xK_1V_T^2$ the current I_3 must therefore be lowered by a value equal to:

$$xK_1(4V_T\sqrt{I_0/K_0} + 4I_0/K_0)$$

As shown in FIGS. 2A and 2B, a current of this value can be subtracted from I_3 using additional transistors M_5 , M_6 and M_7 . Transistors M_5 and M_7 are coupled in series between the ground reference potential line and the output of the current mirror composed of transistors M_2 and M_3 . The gate of transistor M_5 is coupled to the gate of transistor M_1 and the gate of transistor M_7 is coupled to the junction between transistors M_{01} and M_{02} . Transistor M_6 is coupled between the ground reference potential line and the input of the current mirror with its gate coupled to the gate of transistor M_7 .

Transistor M_7 has a wide channel and acts as a voltage follower. Its output voltage V_5 is given by:

$$(13) \quad V_5 \approx \sqrt{I_0/K_0}$$

The current I_5 through transistor M_5 operating in the triode region is:

$$I_5 = K_5[2(V_T + 2\sqrt{I_0/K_0})V_5 - V_5^2]$$

which gives from equation (13):

$$(14) \quad I_5 = K_5(2V_T\sqrt{I_0/K_0} + 3I_0/K_0)$$

By setting:

$$K_5 = 2xK_1$$

gives:

$$(15) \quad I_5 = 2xK_1(2V_T\sqrt{I_0/K_0} + 3I_0/K_0)$$

Now subtracting I_5 from I_3 gives:

$$I_3 - I_5 = xK_1 (V_T^2 - 2 I_0/K_0) \quad (16)$$

This is close to the required value of $xK_1V_T^2$ but still requires the cancellation of the $2 I_0/K_0$ term in order to achieve very high precision for the ratio V_4/V_T .

This can be achieved by adding to current I_1 a current I_6 flowing through transistor M_6 . By setting $K_6=2K_1$ then:

$$I_4 = x [I_1 + I_6] - I_5 = xK_1V_T^2 \quad (17)$$

Current I_4 flowing through transistor M_4 now has the required value and generates a voltage:

$$V_4 = V_T(1 + \sqrt{xK_1/K_4}) \geq V_T$$

if its gate is connected to its drain as shown FIG. 2A or:

$$V_4 = V_T(1 - \sqrt{1 - xK_1/K_4}) \leq V_T$$

if its gate is connected to the gate of the transistor M_1 as shown in FIG. 2B.

The above description refers to an embodiment of the circuit according to the invention in which voltages are generated whose value is proportional to the threshold voltage of the n-channel transistors. To generate voltages proportional to the threshold voltage of the p-channel transistors a circuit complementary to that described above may be used.

I claim:

1. A voltage source circuit comprising:
a current mirror having an input and an output and coupled to a first reference potential line;
a reference current source coupled to the current mirror input for generating a reference current which is proportional to a threshold voltage; and
a bias transistor having a first current electrode coupled to the current mirror output, a second current electrode coupled to a second reference potential line and a control electrode coupled so as to pro-

duce at its first current electrode a voltage dependent on the reference current,
wherein said current mirror output forms an output of the voltage source circuit.

5 2. A voltage source circuit according to claim 1 wherein said reference current source comprises a transistor having a first current electrode coupled to said current mirror input, a second current electrode coupled to said second reference potential line and a control electrode for receiving an input reference voltage which is proportional to the threshold voltage of said transistor of said reference current source.

3. A voltage source circuit according to claim 2 wherein said input reference voltage has a value of substantially twice the threshold voltage of the transistor forming the reference current source.

15 4. A voltage source circuit according to either claim 2 or claim 3 wherein the control electrode of said bias transistor is coupled to receive said input reference voltage.

5. A voltage source circuit according to either claim 2 or claim 3 wherein the control electrode of said bias transistor is coupled to said current mirror output.

6. A voltage source circuit according to claim 3 25 wherein said input reference voltage is produced at the gate electrode of a first diode-coupled transistor coupled via a second diode-coupled transistor to said second reference potential line.

7. A voltage source circuit according to claim 6 further comprising means for adjusting the currents at the input and output of the current mirror in order to correct the voltage at the output of the voltage source circuit.

8. A voltage source circuit according to claim 7 35 wherein the adjusting means comprises a first adjusting transistor coupled in series between said current mirror output and the first current electrode of a second adjusting transistor, the second adjusting transistor having a second current electrode coupled to said second reference potential line, and a gate electrode coupled to receive said input reference voltage and the gate electrode of the first adjusting transistor being coupled to the gate electrode of said second diode-coupled transistor, so as to subtract an adjusting current from the current produced at the output of the current mirror.
